US0D1089081S

(12) **United States Design Patent** (10) **Patent No.:** **US D1,089,081 S**
(45) **Date of Patent:** **** Aug. 19, 2025**

(54) **CHARGING BOX**

(71) Applicant: **Shenzhen Newline Clothing Co., Ltd.**,
Guangdong (CN)

(72) Inventor: **Hongfei Luo**, Guangdong (CN)

(73) Assignee: **Shenzhen Newline Clothing Co., Ltd.**,
Shenzhen (CN)

(**) Term: **15 Years**

(21) Appl. No.: **29/893,802**

(22) Filed: **Jun. 2, 2023**

(30) **Foreign Application Priority Data**

May 12, 2023 (CN) 202330276491.2

(51) **LOC (15) Cl.** **13-02**

CLAIM

The ornamental design for a charging box, as shown and described.

DESCRIPTION

FIG. 1 is a first perspective view of a charging box showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the charging box that form no part of the claimed design.

1 Claim, 8 Drawing Sheets
